(57) **CLAIM**

The ornamental design for a trocar for robotically assisted laparoscopic surgery, as shown and described.

DESCRIPTION

FIG. 1 is a perspective view of a trocar for robotically assisted laparoscopic surgery;

FIG. 2 is a right side elevational view of the trocar;

FIG. 3 is a left side elevational view of the trocar;

FIG. 4 is a front elevational view of the trocar;

FIG. 5 is a rear elevational view of the trocar;

FIG. 6 is a top end plan view of the trocar; and,

FIG. 7 is bottom end plan view of the trocar.

The structural features depicted in broken lines have been shown for purposes of illustrating portions of the trocar that form no part of the claimed design.
